UNITED STATES PATENT OFFICE.

ANTHONY W. SMITH, OF PITTSBURG, PENNSYLVANIA.

DESIGN FOR A PLANT-SUPPORT.

SPECIFICATION forming part of Design No. 22,206, dated February 7, 1893.

Application filed November 22, 1892. Serial No. 452,856. Term of patent 14 years.

To all whom it may concern:

Be it known that I, ANTHONY W. SMITH, a citizen of the United States, residing at Pittsburgh, in the county of Allegheny and State of Pennsylvania, have invented or discovered a certain new Design for Plant-Supports, of which the following is a specification.

The design herein described relates to supports for the branches of plants, &c.

10 In the accompanying drawing forming a part of this specification is shown a perspective view of my design for plant supports.

The leading feature of my design consists in uprights or posts and one or more segmental ribs extending from the posts.

15 The support consists of two approximately

straight posts or uprights 1, and one or more segmental ribs 2 arranged between the posts or uprights, the lower segmental rib, when used, being of the same length as, or a little 20 shorter than the upper rib. A bar 3 is arranged between the ribs about midway of their length.

I claim herein as my invention;
The design for plant supports substantially 25 as herein shown and described.

In testimony whereof I have hereunto set my hand.

ANTHONY W. SMITH.
